Specification for Design.

Patented Apr. 29, 1919.

Application filed June 8, 1918. Serial No. 239,061. Term of patent 14 years.

To all whom it may concern:

Be it known that I, PLINY CATUCCI, a citizen of the United States, residing in the city of Newark, county of Essex, and State of New Jersey, have invented a new, original, and ornamental Design for a Casing for a Phonograph-Motor, of which the following is a specification, reference being had to the accompanying drawings, forming a part thereof.

In the drawings,

Figure 1 is a top plan view illustrating my improved design.

Fig. 2 is a side elevation of the same.

Fig. 3 is an end view looking in the direction of the cylindrical casing.

Fig. 4 is an end view taken from the opposite direction.

I claim:

The ornamental design for a casing for a phonograph motor, substantially as shown.

This specification signed and witnessed this 6th day of June 1918.

PLINY CATUCCI.
